UNITED STATES PATENT OFFICE.

HENRY KELLER, OF NEW YORK, N. Y., ASSIGNOR OF ONE-HALF TO ALBERT A. MEYER, OF SAME PLACE.

GAS-GENERATOR.

SPECIFICATION forming part of Letters Patent No. 611,490, dated September 27, 1898.

Application filed March 19, 1897. Serial No. 628,243. (No model.)

To all whom it may concern:

Be it known that I, HENRY KELLER, a citizen of the United States, residing at New York, in the county of New York and State 5 of New York, have invented certain new and useful Improvements in Gas-Generators; and I do hereby declare the following to be a full, clear, and exact description of the invention, such as will enable others skilled in the art 10 to which it appertains to make and use the same.

My invention relates to certain new and useful improvements in gas machines or generators, the object being to provide a generator 15 of simplified construction whereby the gas may be manufactured at a minimum cost.

To this end my invention consists in certain novel constructions, combinations, and arrangements of parts, as will be hereinafter 20 more fully described, and specifically set forth in the appended claims.

In the accompanying drawing the figure is a central vertical sectional view thereof.

Referring to the drawing, the numeral 1 25 designates a furnace provided with a smoke-stack 2 for the escape of the products of combustion. The furnace is provided with a grate having hollow grate-bars 3, provided with orifices 4, and a steam-supply pipe 5, 30 leading from a suitable source of steam-supply on the exterior, is in connection with the said hollow grate-bars and is adapted to supply steam thereto, which jets or issues through the said orifices and provides a forced draft 35 therefor. Above the grate the furnace is provided with a fuel-feed door 6 and below the same with an ash-door 7 for the removal of the ashes from the ash-pit. A water-supply pipe 8 extends through the wall of the furnace at the ash-pit and is provided with a 40 nozzle 9, arranged to spray jets of water across the lower part of the generator, and a water-overflow pipe 10 extends through the ash-pit wall at the other side and is provided with a 45 vent 11.

A retort or generator vessel 12 is inclosed within the furnace immediately above the grate and is adapted to contain a supply of naphtha or other hydrocarbon oil which is 50 to be treated for the generation of gas. A hydrocarbon-supply pipe 13, leading from the

hydrocarbon-tank on the exterior, is provided to supply the retort with hydrocarbon. This retort is covered by a hood or diaphragm 14, which divides the furnace into two compartments, said diaphragm being provided with an escape flue or pipe 15, through which the smoke, gas, and products of combustion are adapted to escape. A valve 16 is hinged to an extension 17 of this flue and is adapted 60 to seat within the top of the flue and close the same in order to shut off the draft from the furnace-chimney. A lever 18 is connected with this valve, and a chain 18^a leads from the lever to the exterior of the furnace and provides means for opening and closing the said valve. The said flue 15 is in communication with an exhaust-pipe 19, leading into a water-seal chamber or tank 20, which is adapted to prevent the gas from flowing back into the generator. The retort-chamber is also provided at its upper end with a discharge-pipe 21, leading into a condensing-chamber 21^a, and this condensing-chamber has a drip-pipe 22 in communication with a residuum-discharge pipe 75 23, which is provided for removing the waste from the retort. This drip-pipe has a controlling-cock 24. The condenser is also provided with a handhold-plate 25 for removal of the waste therein which cannot pass through 80 the drip-pipe. The condenser is in communication with the water-seal chamber by means of a discharge-pipe 26, leading therefrom. A steam-supply pipe 27, receiving steam from the same source as the steam-supply pipe 5, enters the exhaust-pipe 19 and is provided with a nozzle 28 for discharge of steam thereinto in order to create a draft through the exhaust when the valve controlling the flue-pipe leading from the generator 90 is closed.

The water-seal chamber or compartment 20 is provided with a discharge-pipe 29, adapted to convey the purified gas to the gas holder or reservoir, and a valve 30 is provided in the said pipe for controlling the passage of gas therethrough. The hydrocarbon-supply pipe 13 is provided with an oil-gage 31, having an indicator 32 to indicate the amount of oil contained in the generator. 100 The furnace is provided with a peep-sight 34, whereby the grate and fuel thereon may be

inspected. A tube or pipe 35, leading from the generator, is also provided in order to ascertain the progress of the gas-generating operation, and this pipe has a gas-burner attachment 36 and a drip-chamber 37, provided with a controlling-cock 38.

- The operation is as follows: The fire on the grate is first ignited and the retort heated to a light-cherry heat. Then the ash-door and valve 16 are closed and the water and steam spray turned on to cool the bottom of the generator and create a draft through the exhaust flue or pipe. The hydrocarbon contained within the retort at this time is being quickly vaporized by the heat of the retort, and this gaseous vapor passes through the discharge-pipe 21 into the condenser and then to the water-seal compartment, which prevents it from flowing back to the retort.
- 20 In case more oil is supplied to the retort than it can quickly gasify the gas generated thereby, impregnated with oil and which is heavier than the ordinary gas, passes into the condensing-chamber, where the oil is condensed and the gas discharged into the water-seal compartment, the condensed oil being afterward returned to the retort by means of a return-pipe connection through the condenser to said retort.
- 25 Having thus described my invention, what I claim as new, and desire to secure by Letters Patent, is—
1. In gas-generators, the combination of a furnace having a central division-wall or diaphragm separating it into two compartments, a flue-opening through said division-wall, a retort below the division-wall and immediately above the furnace-grate, a hydrocarbon-supply for the retort, a valve controlling the 30 flue-pipe leading from the division-wall, a condenser on the exterior and in communication with the retort, a water-seal chamber having a pipe connection with the condenser, and an exhaust-pipe communicating between the said flue and the water-seal chamber, substantially as and for the purpose described.
2. In a gas-machine, the combination of the furnace provided with a valve-controlled exhaust-passage, a retort contained therein and 35 provided with a hydrocarbon-supply pipe, a

condensing-chamber on the exterior and provided with a discharge for the condensed oil into the retort and in communication with the latter to receive the gas therefrom, and a water-seal chamber in communication with the said condenser and exhaust-pipe, substantially as described.

3. In gas-generators, the combination of a furnace having a central division-wall or diaphragm separating it into two compartments, a flue rising from said diaphragm and provided with a valve, a retort having position immediately below the division-wall and above the furnace-grate, a water-seal chamber, a condensing-chamber having supply and discharge connections with the said retort and a discharge-pipe leading into the said water seal, and an exhaust-pipe in the furnace leading from the said flue to the water-seal chamber, substantially as described.

4. In gas-generators, the combination of a furnace having a central division-wall or diaphragm separating it into two compartments and a smoke-stack above the same, a flue projecting from said division-wall and arranged in a direct vertical line below the said smoke-stack, said flue having a valve to prevent the gas from the furnace passing out of said stack, a retort or generator located in the lower chamber of the furnace between the said diaphragm and the grate, a hydrocarbon-supply to said retort, a water-seal chamber, a valve-controlled discharge-pipe leading therefrom, a condensing-chamber interposed between the said water-seal chamber and the retort and provided with a discharge-pipe leading into said water-seal chamber and having supply and discharge connections with the said retort, and a discharge-pipe leading from the flue in the diaphragm and having its outer end opening into the water-seal chamber, substantially as and for the purpose described.

In testimony whereof I have signed this specification in the presence of two subscribing witnesses.

HENRY KELLER.
